CLAIM

The ornamental design for a combined hat and party blowout, as shown and described.

DESCRIPTION

FIG. 1 is a perspective view of a combined hat and party blowout showing my new design;

FIG. 2 is a bottom plan view thereof;

FIG. 3 is a top plan view thereof;

FIG. 4 is a side elevational view thereof with the blow-out partially extended; and

FIG. 5 is a bottom plan view of a second embodiment thereof, the perspective view and top plan view are the same as FIGS. 1 and 3.
